CLAIM

(22) Filed: **Apr. 13, 2015**

I claim the ornamental design for a tablet case with camera block sliders, as shown and described.

(51) **LOC (10) Cl.** **14-02**
(52) **U.S. Cl.**

DESCRIPTION

USPC **D14/440**

(58) **Field of Classification Search**

FIG. 1 is a front, bottom, left perspective view of the tablet case with camera block sliders shown in broken lines within the case.

USPC D14/250, 440, 447; 206/45.23, 320,
206/45.2; 361/679.55; 294/25; 224/218
CPC ... G06F 1/1628; G06F 1/1613; G06F 1/1626;
A47B 23/044

FIG. 2 is a rear, top, left perspective view of the tablet case with camera block sliders shown in broken lines within the case.

See application file for complete search history.

FIG. 3 is a front elevation view of the tablet case with camera block sliders shown in broken lines within the case.
